Patented Apr. 27, 1971

220,600

FRONT WHEEL DRIVE SIDEWALK BICYCLE

Loran R. Hill, Olney, Ill., assignor to American
Machine & Foundry Company

Filed Sept. 17, 1969, Ser. No. 19,194

Term of patent 14 years

Int. Cl. D12—11

U.S. Cl. D90—8

FIG. 2

FIG. 1

FIG. 4

FIG. 3

FIG. 1 is a perspective view of a bicycle having my design;

FIG. 2 is a side elevation view of the bicycle;

FIG. 3 is a top plan view of the bicycle; and

FIG. 4 is a rear elevation view of the bicycle.

I claim:

The ornamental design for a front wheel drive sidewalk bicycle, substantially as shown.
